JEROME SANDIN, OF WILKINS TOWNSHIP, ALLEGHENY COUNTY, PENNSYLVANIA, AS
SIGNOR TO WESTINGHOUSE ELECTRIC & MANUFACTURING COMPANY, A CORPOR-
ATION OF PENNSYLVANIA

FUSE BOX

Application filed January 14, 1927. Serial No. 161,057.

My invention relates to fuse mechanisms and particularly to enclosed expulsion fuses.

One object of my invention is to provide an adjustable terminal for a fuse tube clip 5 disposed within a housing, that may be connected to an electrical circuit from either side of said housing.

Another object of my invention is to provide a fuse tube having a shoulder for engaging a supporting insulating member in such manner that the reactive shock, incident to the disruption of the fuse will be absorbed in the lower part of the insulated supporting member by subjecting it to a 10 direct compressional strain, thereby eliminating the possibilities of fracture that heretofore existed when the insulating supporting member was subjected to stresses transferred by cantilever or direct shearing 15 strains.

A further object of my invention is to provide a fuse housing from which the fuse tube projects to eliminate the formation of an arc and arc gases within the housing.

It is frequently desirable that electrical conductors from either side of a housing may be attached to the upper or lower fuse clip terminals of a fuse box. Heretofore the changing of a porcelain insulator from an 20 upper to a lower hole in the side of the housing or vice-versa was common practice in making such changes in the connections. I eliminate the extra hole in each side of the housing and mount the porcelain insulators 25 directly opposite to each other by changing an enclosed adjustable terminal rather than the insulators.

My invention also provides a shoulder element at the lower end of the fuse for 30 abutting against the lower end of an insulating supporting member whereby the shock incident to the disruption of the fuse is absorbed by the lower part of the insulating supporting member by subjecting it to stresses 35 in direct compression.

My invention further provides a hole in the bottom of the fuse housing to or beyond the bottom of which the expulsion end of the fuse tube projects when the door of the 40 housing is closed, thereby liberating the arc

and arc gases exteriorly of the fuse housing and eliminating the use of arc barriers between the fuse terminals.

These and other objects are attained by the construction herein described and illustrated in the accompanying drawings, in which

Fig. 1 is a side view, partly in section and partly in elevation of my enclosed expulsion fuse mechanism; and

Fig. 2 is a broken front view of the apparatus shown in Fig. 1, with the cover and fuse cartridge removed.

Referring to the drawings, a housing 1 comprises a door 2, a rear panel 3, side walls 4 and 5 of wood, a metal cover 6 and a perforated bottom 7. The side walls 4 and 5 have two opposite, diagonal holes 8 and 9 that support insulating bushings 10 and 11.

The rear panel 3 supports an insulating member 12, by bolts 13, that has supported thereon fuse tube clips 14 and 15 by bolts 16. An adjustable terminal member 18 is attached to the lower fuse clip 14 by screws 19 for clamping it in position on either side of the stop 20. An electrical conductor 22 extends from the insulating bushings 10 and engages the adjustable terminal 18. Another electrical conductor 23 extends from the insulating bushing 11 and is connected to the fuse tube clip 15 at its terminal 24. The relative positions of the conductors 22 and 23 with respect to the bushings 10 and 11 may be reversed as desired. The door 2 is hinged to the side walls 4 and 5 by hooks 25 that engage with pins 26 and supports an insulating member 27 that is secured thereto by bolts 28.

A fuse tube 29 is supported on the insulated member 27 by pins 31 and may be removed with the insulating member 27 and the door 2 by the disengagement of the hooks 25 from the pins 26. The fuse tube 29 has a bushing 32 that abuts against the lower face of the insulating member 27 and projects to or beyond a perforation 33 in the bottom 7 of the housing 2.

On loosening the nuts 19, the terminal 18 may be moved to the right of the stop 20, to engage the conductor 22, or to the left of the

stop 20 to engage the conductor 23, thereby eliminating the necessity of changing the insulators in the field to meet the line conditions.

5 Upon closing the door 2 of the housing 1, the expulsion or lower end of the fuse 29 projects to or beyond the bottom 7 of the housing; whereby the arc and arc gases are ejected from the fuse tube 29 from without the 10 fuse housing 1.

The shoulder member 32 of the fuse tube 29, abutting against the lower face of insulating member 27, transfers the shock incident to the rupturing of the fuse 29 to the 15 lower portion of the insulating member 27 and subjects it to stresses in compression that limit the possibility of breaking the member and thus prevents the longitudinal movement of the fuse.

20 Accordingly, my invention embodies a fuse tube supporting member, part of which is subject to compressional strains when absorbing the shock incident to fuse rupture, thereby limiting the danger of breaking the 25 supporting member that often occurs when it is subjected to strains in cantilever or direct shear. My invention also simplifies the work of maintaining and installing the fuse 30 housings in the field as the porcelain insulators for the conducting members are permanently located in the side walls of the housing thereby eliminating the necessity for rearranging them to meet changing conditions, as has been the practice heretofore. It further 35 simplifies the details of construction of the housing by the omission of a barrier from between the terminal members of the fuse because the expulsion end of the fuse tube projects to or beyond the bottom of the housing.

40 It is to be understood that such changes in the form, arrangement and connection of the component parts of my invention may be made as shall fall within the scope of the appended claims.

45 I claim as my invention:

1. A fuse structure comprising a housing, a pair of bushings associated therewith in angular relation to each other, a fuse tube, an insulating member within the housing 50 having means for engaging the terminals of the fuse tube, one of the engaging means having a terminal member adapted to be adjusted to any one of a plurality of positions.

2. In a fuse structure, the combination with 55 a fuse, of a housing therefor, an insulating member within the housing having conducting members mounted thereon for engaging the terminals of the fuse tube, one of the conducting members having an adjustable terminal 60 adapted to be moved to engage a conductor extending from either side of the housing and clamping means on the end of the terminal for engaging the conductor.

3. In combination with an expulsion fuse, 65 a housing having a pair of oppositely dis-

posed bushings for the reception of electrical conductors, means for mounting the bushings in angular relation to each other, conducting members for engaging the terminals of the fuse tube and a movable terminal associated 70 with a conducting member for engaging a conductor extending from either one of the angularly disposed bushings.

4. The combination with an enclosed expulsion fuse, of a housing, a hinged door 75 therefor having an insulating member thereon, a shoulder member on the expulsion fuse tube in proximity to its expulsion end and engaging the insulating member whereby the reactive shock incident to the disruption of 80 the fuse is absorbed by the lower part of the insulating member.

5. The combination with an enclosed expulsion fuse, of a housing, a hinged door 85 therefor having an insulating member thereon, a shoulder member on the expulsion fuse tube in proximity to its expulsion end and engaging the insulating member, whereby the recoil in the expulsion fuse will subject the lower part of the insulating member to 90 compressional strains that absorb the shock therefrom and retain the fuse tube in its original position.

6. The combination, in a fuse housing having a single pair of oppositely disposed bushings for the reception of electrical conductors, of a swinging terminal therefor, a stop member for positioning the terminal, and clamping means for holding the terminal in fixed 95 position.

7. The combination, in a fuse housing having a single pair of oppositely disposed bushings for the reception of electrical conductors, means for supporting a fuse with its axis normal to a plane through said bushings, a terminal movable to engage a conductor from either of said bushings and clamping means for the conductor on the end of the terminal. 105

8. The combination with a fuse housing, of a pair of bushings for the reception of electrical conductors disposed in a plane perpendicular to the fuse axis, means for supporting the said bushings in angular relation to the said housing, a terminal movable into engagement with the conductor from either of said bushings, and clamping means for holding the terminal in fixed position. 110

In testimony whereof, I have hereunto subscribed my name this 6th day of January, 1927.

120 JEROME SANDIN.
